(57) CLAIM

The ornamental design for a pan handle, as shown and described.

DESCRIPTION

FIG. 1 is a bottom view of my new design relating to pan handle;

FIG. 2 is a left side view thereof;

FIG. 3 is a top view thereof;

FIG. 4 is a right side view thereof;

FIG. 5 is a front end view thereof;

FIG. 6 is a rear end view thereof; and,

FIG. 7 is a top/left/rear perspective view thereof.

The broken lines represent portions of the design that form no part of the claim.
